UNITED STATES PATENT OFFICE.

LAURITZ W. ANDERSEN, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

SHADE-HOLDING MEANS FOR ELECTRIC FIXTURES.

1,097,282.

Specification of Letters Patent. Patented May 19, 1914.

Application filed September 18, 1913. Serial No. 790,547.

To all whom it may concern:

Be it known that I, LAURITZ W. ANDERSEN, a citizen of the United States, residing at Waterbury, in the county of New Haven and State of Connecticut, have invented a new and useful Improvement in Shade-Holding Means for Electric Fixtures, of which the following is a specification.

This invention relates generally to electric light fixtures and more particularly to a portable lamp fixture.

The portable fixture to which my invention is particularly adapted embraces in its construction a suitable support for the incandescent lamp socket and in connection with this support is employed a shade or reflector which shade or reflector is pivotally connected to a shade holder which is adapted to the socket support.

In the portable lamp to which my invention is particularly adapted the socket support has comprised a ball joint as a part thereof so that various adjustments could be obtained and in connection with the shade or reflector the light could be directed in various ways but in order to provide for still further adjustments whereby a still further direction of the light could be obtained I provide for the adjustment of the shade holder upon its support and also means for holding said shade or reflector holder at any desired point of adjustment.

The present invention therefore consists in providing a rotatably adjustable shade holder or support upon the lamp support and in providing frictional means for holding said shade holder at any desired point of adjustment.

The invention consists also in certain details of construction hereinafter fully described and pointed out in the claims.

In the drawings forming a part of this specification:—Figure 1 is a perspective view of a portable lamp embodying my invention, the shade holder being shown in one adjustment, and, Fig. 2 is a similar view showing the shade holder adjusted to a different position. Fig. 3 is an enlarged view of the frictional holding means. Fig. 4 is a detail sectional view, and, Fig. 5 is a

detail perspective view of the spring friction plate.

Referring to the drawings A indicates a pedestal or support which comprises in its construction a ball joint B such as shown 55 and described in my application for patent filed September 6, 1913, Serial Number 788,418, patented December 2, 1913, Number 1,080,405.

Connected to the pedestal or support is 60 the lamp socket C, this socket being of any desired or approved construction. In connection with this portable lamp I employ a shade or reflector D which is pivotally connected to the ends of a shade holder E, which 65 is in the form of a U-shaped bracket which is fixed in any suitable manner to a small metallic block D' centrally bored for arrangement upon the socket support or pedestal. Arranged also upon the socket support or pedestal and interposed between the socket and shade holder is a spring friction plate F, the ends F' of which are bent back and under and are adapted to contact with the central portion of the shade holder, this 75 plate being of such size, shape and construction as to provide sufficient frictional contact between the parts so that the shade or reflector holder can be rotated upon the support but will be held at any desired point of 80 adjustment. This is a very important feature when taken into combination with the adjustment of the ball joint in the support and the shade or reflector adjustment upon the holder, as by making the holder rotatably 85 adjustable and locking the same frictionally at any desired point of adjustment I am able to adjust the shade or reflector at any point it may be deemed necessary in order to direct the rays of light in the proper direction. 90

While I have shown and described my invention as applied to a portable lamp, it will be understood that the invention is adapted for use in connection with other forms of fixtures so long as the rotatable 95 shade or reflector holder is rotatably mounted upon the socket support.

What I claim is:—

The combination with a support comprising a ball joint as a part thereof, a shade 100

holding bracket arranged upon said support and adapted to turn thereon, a spring friction plate arranged also upon said support, a socket arranged upon the end of 5 said support and adapted to maintain the spring friction plate in contact with the shade holder bracket, and a combined shade and reflector pivotally connected to the ends of the shade holding bracket substantially as set forth.

LAURITZ W. ANDERSEN.
